UNITED STATES PATENT OFFICE.

ROBERT E. L. JANNEY, OF CHICAGO, ILLINOIS, ASSIGNOR TO AMERICAN STEEL
FOUNDRIES, OF NEW YORK, N. Y., A CORPORATION OF NEW JERSEY.

GUARD-ARM FOR COUPLINGS.

1,223,491.

Specification of Letters Patent. Patented Apr. 24, 1917.

Application filed October 14, 1916. Serial No. 125,539.

To all whom it may concern:

Be it known that I, ROBERT E. L. JANNEY, a citizen of the United States, and resident of Chicago, in the county of Cook and State 5 of Illinois, have invented certain new and useful Improvements in Guard-Arms for Couplings, of which the following is a specification.

My invention relates to car couplers and 10 has particular reference to a novel guard arm construction.

It is well known that car couplers are subjected to severe strains and that the guard arm receives many of the most severe of 15 these strains. It is an object of the present invention to provide a reinforcement for the guard arm, the metal being so distributed as to provide for a maximum efficiency. Not only is it desirable to provide for the 20 maximum resistance to strain, but likewise for ease in the production of the casting. To this end means should be provided for supporting the cores. If such means are not provided, many faulty castings will be produced due to the shifting of the cores. The 25 desired result as to all these particulars is secured in the structure illustrated herewith.

In the drawings

Figure 1 is a side elevation of a car 30 coupler, the view being taken from the guard arm side.

Figs. 2 and 3 are sectional views taken on the lines 2—2, 3—3, respectively, of Fig. 4, and Fig. 4 is a plan view partly in section.

35 The construction herein disclosed is intended as an improvement on construction of my application, Serial Number 41869, filed July 26, 1915.

In the drawings it will be seen that the 40 coupler head 10 is provided with the usual ears 11 and a guard arm consisting of a vertical wall or web 12, which is suitably reinforced by means of the converging upper and lower webs 13, 14 and the intermediate 45 horizontal web 15. These webs or ribs merge into or join the vertical wall 12 at the extremities of the webs. In order to brace and add materially to the effectiveness of the converging webs 13, 14, I unite the 50 margins thereof at points intermediate the

ends of the webs with the wall 12 by means of the webs 16, 17. The webs 16, 17 are discontinued to provide the openings 18, 19, best shown in Fig. 4. By providing these openings 18, 19 I am enabled to support the 55 cores by anchoring the same in the adjacent mold. This is an important advantage as the exact placing of the cores is responsible for the production of walls the correct thickness. While I have shown the webs 16, 17 60 as extending horizontally, and this is the preferred construction, yet substantially the same advantages would accrue if the webs were not so placed. The object is to provide a brace or strut which will serve to prevent 65 the collapsing or distortion of the converging webs.

It will be understood also that the exact form and arrangement is not essential to the advantageous utilization of the invention 70 and that modifications may be made therein without departure from the spirit thereof.

I claim:

1. In a guard arm for car couplers, the combination of a vertical wall, converging 75 outer webs, and webs joining the edges of said converging webs to said vertical wall, substantially as described.

2. A car coupler guard arm having a vertical wall, converging outer strengthening 80 webs, an intermediate horizontal strengthening web, and webs joining the edges of said converging webs to said vertical wall, substantially as described.

3. A car coupler guard arm including a 85 vertical wall, inclined outer stiffening webs and an intermediate horizontal web, and stiffening webs joining the edges of said inclined webs to said vertical wall, said stiffening webs being apertured to provide 90 a passage between the cavity inclosed by said webs and the space adjoining said horizontal web, substantially as described.

Signed at Chicago, Illinois, this 11th day of October, 1916.

ROBERT E. L. JANNEY.
